(57) **CLAIM**

The ornamental design for a speaker housing, as shown and described.

DESCRIPTION

FIG. 1 is a perspective view of a speaker housing showing my new design;

FIG. 2 is a reduced top plan view thereof;

FIG. 3 is a front elevational view thereof;

FIG. 4 is a side elevational view thereof, the opposite side elevational view being a mirror image thereof; and,

FIG. 5 is a back elevational view thereof.

The broken line defining the top edge of the speaker on FIGS. 1-3 represents the bounds of the claimed design and form no part thereof. The broken line showing of the footing in FIGS. 1 and 3-5, the speaker driver areas in FIGS. 1-3 and the control element in FIGS. 1-5 is for illustrative purposes only and forms no part of the claimed design.
